(57) **CLAIM**

The ornamental design for a bowl stabilizer, as shown and described.

DESCRIPTION

FIG. 1 is a front-top perspective view of a bowl stabilizer, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom-rear perspective view thereof;

FIG. 9 is a front-top perspective view thereof, shown in a folded configuration;

FIG. 10 is a front elevational view thereof, shown in a folded configuration;

FIG. 11 is a rear elevational view thereof, shown in a folded configuration;

FIG. 12 is a left side elevational view thereof, shown in a folded configuration;

FIG. 13 is a right side elevational view thereof, shown in a folded configuration;

FIG. 14 is a top plan view thereof, shown in a folded configuration; and,

FIG. 15 is a bottom plan view thereof, shown in a folded configuration.

1 Claim, 8 Drawing Sheets
